UNITED STATES PATENT OFFICE.

ALVAH SWEETLAND, OF SYRACUSE, NEW YORK.

HINGE.

SPECIFICATION forming part of Letters Patent No. 256,405, dated April 11, 1882.

Application filed July 15, 1881. (Model.)

To all whom it may concern:

Be it known that I, ALVAH SWEETLAND, of Syracuse, in the county of Onondaga, in the State of New York, have invented new and useful Improvements in Gate and Door Hinges, of which the following, taken in connection with the accompanying drawings, is a full, clear, and exact description.

This invention relates to that class of hinges which automatically close the gate or door by means of one leaf or bracket of the hinge riding on a cam or inclined bearing on the other leaf or bracket.

Although hinges operating as aforesaid are very desirable, yet they have failed to come into extensive use, owing chiefly to the excessive cost of their manufacture and their liability of becoming clogged or broken by ice and snow gathering around the pivotal connection of the hinge.

It is to overcome these defects which my invention has for its object; and to that end it consists in the peculiar construction of the constituent parts of the hinge, as hereinafter fully described, and specifically set forth in the claim.

In the annexed drawings, Figure 1 is a side view of my invention as applied to a gate, showing the same in a closed position. Fig. 2 is a view facing the post, and showing the operation of my improved hinge when the gate is opened. Fig. 3 is an enlarged inverted plan view of the male part of the hinge, and Fig. 4 is a top view of the female part of the hinge.

Similar letters of reference indicate corresponding parts.

A and B represent the two brackets or attaching-plates of the hinge, the one constituting the male part of the hinge and being attached to the gate, and the other the female part of the hinge, attached to the post. The bracket A has on its outer or rear face a rigid and solid horizontal plate, s, from the center of the bottom of which projects the gudgeon or pintle a. Around the said pintle, and concentric therewith, is a double-inclined track or cam, r, in the form of an annular rim on the under side of the plate s, the bottom edge of which rim is beveled or inclined from a point between the pintle and attaching-plate rearward, giving the outer or rear portion thereof the greatest depth. The bracket B is provided with a

socket, b, in which is pivoted and adapted to slide vertically the pintle a of the bracket A. The socketed plate b, I provide on the side farthest from its attaching-plate with a rigid stud 55 or pintle, upon which I mount detachably a roller, c, having on the side adjacent to the plate a peripheral flange. The rim or cam r of the bracket A rides upon the roller c, and the engagement of the inner edge of said rim 60 with the flange of the roller c serves to retain said roller upon its pintle. The shallow portion of the cam r, being nearest the bracket or attaching-plate A, causes the gate by its gravity to normally stand in a closed position. 65

Upon opening the gate the deeper portion of the cam r is carried upon the roller c, thereby producing on the gate an upward pressure, which lifts the same bodily. Upon releasing the opened gate it descends by its gravity, and is 70 simultaneously swung into a closed position by the travel of the cam r upon the roller c. The double incline of the said cam allows the gate to swing in either direction, and the junction of said inclines determines the movement 75 of the gate to its closed position. In order to render the latter more positive, I increase the angle of inclination at the junction of the inclines.

It will be observed that by bringing the roller 80 c to bear on the rim r between the gate and its pivot a most effective support for the gate is obtained and the pintle of the hinge is greatly relieved of lateral strain.

My improved hinge is perfectly protected 85 against snow and ice by the plate s and its rim r forming a cap, covering and shielding the pivotal connection.

It is obvious that by a slight modification in the form of the attaching-plates of the de- 90 scribed hinge the same may be adapted to be applied to a door as well as a gate.

I do not claim broadly a hinge having one of its brackets riding on an inclined track or a cam on the other bracket, as I am aware the 95 same is not new; but

I do claim as a specific improvement in that class of hinges—

The improved gate-hinge, consisting of the bracket B, having the socket b, provided on the side farthest from the attaching-plate with a rigid journal, the roller c, mounted on said

journal and provided with a peripheral flange on the side adjacent to the bracket B, the bracket A, having a solid plate, *s*, covering the socket *b*, and provided with the rigid downward-projecting pintle *a* and the concentric double-inclined rim *r*, the latter riding on the roller *c* and engaging with its inner edge the flange of said roller, all constructed substantially in the manner described and shown.

In testimony whereof I have hereunto signed my name and affixed my seal, in the presence of two attesting witnesses, at Syracuse, in the county of Onondaga, in the State of New York, this 8th day of July, 1881.

ALVAH SWEETLAND. [L. S.]
